United States Patent Office

Des. 180,385
Patented June 4, 1957

180,385

TRACK SHOE

Bernard A. Bellew, Los Angeles, Calif.

Application December 6, 1956, Serial No. 44,087

Term of patent 14 years

(Cl. D7—7)

FIG. 1.

FIG. 2.

FIG. 3.

FIG. 4.

FIG. 5.

Figure 1 is a side elevational view of my new design for the track shoe;

Figure 2 is a top plan view thereof;

Figure 3 is a bottom plan view thereof;

Figure 4 is a front view thereof; and,

Figure 5 is a rear view thereof.

I claim:

The ornamental design for a track shoe, substantially as shown.

References Cited in the file of this patent

UNITED STATES PATENTS

D. 118,137	Pick	Dec. 19, 1939
D. 170,783	Wegner	Nov. 3, 1953
2,660,813	Shapiro	Dec. 1, 1953